UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,851**, dated September 2, 1873; application filed August 9, 1873.
[Term of Patent 3½ years.]

M.

To all whom it may concern:

Be it known that I, FREDERICK WINK, of Philadelphia, Pennsylvania, have invented a Design for Shawl-Pattern, of which the following is a specification:

My design for a shawl-pattern is fully represented by the figure in the accompanying drawing, the remainder being merely a repetition of that which appears.

The pattern is composed of two parallel strips, A and B, upon a plain ground, D, each of the said stripes having a central rib, a, elaborately ornamented by dots, &c., in a manner so clearly shown in the drawing as to require no minute description, the said stripes being otherwise composed of minor parallel

stripes, bars, or ribs of different widths and varying shades or colors, and the said stripe A having also several rows of dots, staggered as shown.

Irrespective of the colors employed, I claim—
The design for a shawl-pattern, as described, and as illustrated in and by the accompanying drawing.

In testimony whereof I have signed my name to this specification in the presence of two subscribing witnesses.

FRED. WINK.

Witnesses:

CLINTON M. LATOURETTE,
LEWIS T. GODFREY.
